UNITED STATES PATENT OFFICE.

FRANCIS E. OWEN, OF THISTLE, UTAH.

TWISTER FOR LOCOMOTIVE EXHAUST NOZZLES.

Application filed August 4, 1920. Serial No. 401,252.

To all whom it may concern:

Be it known that I, FRANCIS E. OWEN, a citizen of the United States, and a resident of the town of Thistle, in the county of 5 Utah and State of Utah, have invented a certain new and useful Twister for Locomotive Exhaust Nozzles, of which the following, together with the accompanying drawing, forms a full, clear, and exact specification, such as will enable others skilled in 10 the art to which it appertains to make and use the same.

This invention relates to a twister for locomotive exhaust nozzles and its principal 15 objects are:

First. To impart a helical motion to the stream of exhaust steam of a locomotive as it emerges from the nozzle.

Second. To create a more perfect vacuum 20 in the smoke-box of a locomotive than is obtained by present-day methods, thereby relieving the back pressure on the pistons.

Third. To obtain a greater efficiency in 25 the use of the fuel for the locomotive, by eliminating the waste of energy due to the impeded exit from the smoke-box, of the exhaust steam and the gases resulting from the combustion of the fuel.

Fourth. To furnish the equivalent of a 30 considerable increase of the effective cross-sectional area of the exhaust pipe.

In attaining the objects above mentioned, I provide, what I choose to call a "twister." This twister comprises a series of vanes or 35 blades, which are preferably helical in form and which radiate from a vertical axis more or less coincident with the axis of the nozzle. The vanes or blades may spread outwardly until the edges thereof contact the 40 peripheral inside surface of the nozzle, to the walls of which the blades may be fastened by any suitable means. The top of the twister preferably lies in a plane at right angles to the axis thereof and may be flush 45 with the top of the nozzle. The blades may extend downwardly through the nozzle and may project a reasonable distance into the exhaust pipe.

The effect of the twister is to cause the 50 exhaust steam, as it emerges from the nozzle, to rush upwardly with a twisting or swirling motion, thereby creating a more perfect vacuum in the smoke-box than is accomplished by the plain nozzles in use at the 55 present time and bringing about a considerable saving in fuel.

The features of this invention upon which the protection of Letters Patent is desired, are collectively grouped in the claims.

In the drawing,

Fig. 1 represents a plan view of an ordinary locomotive exhaust nozzle with one embodiment of my invention operatively disposed therein, and

Fig. 2, a vertical section on line 2—2 in 65 Fig. 1, showing the said embodiment in elevation.

Referring to the drawing, the numeral 10 designates an ordinary exhaust nozzle fastened to the usual exhaust pipe 12, by the 70 bolts 14. Parts 15, 16 and 17, represent radially disposed vanes or blades intersecting each other in the axis of the nozzle and having their longitudinal junction line reinforced so as to form a circular cylindrical 75 hub 18. The vanes 15, 16 and 17 may be fastened to the nozzle wall by means of the rivets 15^a, 16^a and 17^a, though if desired, the vanes may be fastened to the nozzle by autogenous welding, or the vanes might 80 be cast integrally with the nozzle proper. The vanes 15, 16 and 17 may project downwardly into the exhaust pipe 12 to any reasonable depth, as shown in Fig. 2, and the bottom edges of the vanes may be shaped 85 to a feather edge, so as to offer a minimum of resistance to the oncoming exhaust steam. The vanes are curved in horizontal cross-section, that is, a section taken perpendicularly to the axis of the twister 90 shows the vanes in the form of cupped channels. The number of vanes used and the pitch of the helicoids formed thereby, may be varied to suit individual requirements.

Having fully described my invention, what I claim is:

1. In a twister for locomotive exhaust nozzles, the combination with a nozzle portion, of a plurality of vanes inside the said nozzle portion, the said vanes having a curved cross-section and being inclined, relatively to the longitudinal axis of the said nozzle portion, for the purpose of imparting a twisting motion to fluids discharged from the said nozzle portion.

2. A nozzle portion and a plurality of helicoidal vanes, the said helicoidal vanes having a curved cross-section and their outer edges joined to the interior surface 110 of the said nozzle portion, for the purpose specified.

3. A nozzle portion, a plurality of helicoidal vanes having a channel cross-section concentrically disposed with relation to the said nozzle portion and located inside 5 thereof, for the purpose specified.

4. A nozzle portion having a longitudinal axis, a plurality of helicoidal vanes of curved cross-section spaced around the said axis, a hub portion joining the said vanes 10 to each other, and means for fastening the said vanes to the interior surface of the said nozzle portion.

5. A twister for locomotive nozzles, the 15 said twister comprising a longitudinal circular cylindrical hub, a plurality of cupped

helicoidal vanes extending outwardly from the said hub, the said vanes being spaced around the axis of the said hub and adapted for fastening to the inside of a locomotive nozzle.

6. In a locomotive nozzle a plurality of helicoidal vanes extending longitudinally along the axis thereof, the said vanes being shaped in such a manner, that sections taken transversely through the said vanes 20 shall show channeled forms for the purpose specified.

In testimony whereof I sign my name hereto.

FRANCIS E. OWEN.
